GAS-TIME METER

Fred E. Wood, Glen Ellyn, Ill.

Application August 8, 1932, Serial No. 627,981

14 Claims. (Cl. 194—13)

This invention relates to a gas time meter and more particularly to coin-controlled apparatus for controlling a valve in a gas supply line for a predetermined period.

An object of the invention is to provide simple means, actuated by coins, for opening and maintaining open for a predetermined period or periods, a valve in a fuel supply line leading to a gas range, or any other device or apparatus which consumes gas. A further object is to provide an improved gas time meter adapted to receive a number of coins and to permit the flow of gas for a predetermined period or periods while at the same time exacting a penalty in the form of the loss of a coin or coins should anyone attempt to tamper with the driving mechanism or break the electrical connections therefor. A further object is to provide improved valve and valve-control means which operate automatically under certain conditions and which permit a constant flow of a small quantity of gas sufficient to maintain the pilot light. Other objects and advantages will appear as the specification proceeds.

The invention is described, in a preferred embodiment, in the accompanying drawings, in which:

Fig. 1 is a longitudinal sectional view of apparatus embodying my invention, the section being taken as indicated at line 1 of Fig. 2; Fig. 2, a plan sectional view, the section being taken as indicated at line 2 of Fig. 1; Fig. 3, an enlarged plan detail view of a member actuated by the coins; Fig. 4, a transverse sectional view, the section being taken as indicated at line 4 of Fig. 1; and Fig. 5, an enlarged sectional view, the section being taken as indicated at line 5 of Fig. 4.

In the embodiment illustrated, the apparatus is illustrated as being employed in connection with a gas range or a device requiring a small amount of gas to be constantly fed thereto.

In the illustration given, A designates a motor; B, coin-controlled mechanism for closing the circuit in which the motor is placed; C, coin-release means; D, reduction-speed gear mechanism for actuating the coin-release mechanism C; E, valve-control means; and F, gas valve mechanism.

The apparatus just mentioned is preferably housed within a casing 10 which is preferably closed so as to prevent access to the working parts. The casing provides on one side a coin receptacle 11 to which access may be had by a key-controlled door (not shown).

The motor A is supported within the casing 10 by any suitable means. While the driving

mechanism is illustrated in the form of a motor, it will be understood that any other suitable driving means may be substituted. As shown more clearly in Figs. 1 and 2, the motor A is placed within a circuit adapted to be closed by a coin-controlled mechanism B.

The mechanism B comprises a coin slot 12 adapted to receive a plurality of coins, as for example quarters, the coins being supported by the release mechanism C. On one side, the coin slot 12 is broken away, as indicated at 13, to permit the swinging levers 14 and 15 to extend into the slot 12. The levers 14 and 15 are, as shown more clearly in Fig. 3, provided with spaced attachment ears 16 which are perforated and which lie adjacent the bracket flanges 17. The parts 16 and 17 are secured together by stud 18. A spring 19 is carried by the stud 18 and the ends of the spring are positioned so as to urge the lever in an upward position. The bracket 17 is secured by flanges 20 to a wall of the casing 10. On their bottom sides, the levers 14 and 15 are provided with contact fingers 21 adapted to engage the contact plates 22 carried by the flanges 20. The wire 23 is connected to the plates 22 and the wire 24 is connected with contact fingers 21 and one terminal of motor A. As shown more clearly in Fig. 2, an outlet wire 25 is connected to the other terminal of the motor A. With this arrangement, when either of the contact fingers 21 is brought in contact with one of the plates 22, the circuit is completed and motor A should be set in operation. The coins in the coin slot 12 are indicated by the numeral 26.

The coin-release mechanism C consists of a plate member 27 of the shape illustrated having a lower forwardly inclined catch portion 28 adapted to engage the lower side of the coin and having a forwardly extending check or catch 29 at its upper side adapted to engage the upper coin so as to prevent it from falling while the lower coin is being released. The member 27 is provided with a rearwardly extending shank 30 which is pivotally connected to the top of standard 31. At its rear side, the shank 30 is pivotally connected to a lever 32 which in turn is pivotally supported upon standard 33. The lever 32 is provided with a vertical finger 34 and with a rearwardly extending arm 35.

The reduction gear mechanism D is provided with means for striking the vertical finger 34 and actuating the release mechanism C. In the illustration given, the specific means employed for this purpose consists of a rotatably mounted

disk 36 equipped with an adjustable plate 37. The plate 37 carries a pin 38 which, upon rotation of the disk 36 in a counter-clockwise direction, strikes the vertical finger 34. As shown 5 more clearly in Fig. 1, the plate 37 is provided with a longitudinal slot 39 through which extends a set screw 40. The disk 36 is carried upon shaft 41 which is rotatably supported in bracket 42. Upon the end of the shaft 41 is mounted a 10 worm gear 43 driven by worm 44. The worm 44 carries upon its free end a large gear 45 which meshes with pinion 46. The pinion 46 is driven by a series of gears indicated by the numeral 47. The gears 47 are connected to the pinion 48 carried by the drive shaft 49 of the motor A. While, for purposes of illustration, a specific set of reduction gears are shown, it will be understood 15 that any suitable connecting means between the motor A and disk 36, by which the latter may be rotated slowly, say once in twenty-four hours, 20 may be employed.

The valve control mechanism E is also driven by the pinion 48 on the motor shaft 49. As shown more clearly in Fig. 1, a gear 50 meshes with 25 pinion 48 and is fixed upon shaft 51. Shaft 51 carries gear 52 which meshes with gear 53 on shaft 54. The shaft 54 is supported by bracket 55 and carries a bevel pinion gear 56. Gear 56 drives a large bevel gear 57 carried upon shaft 30 58. The shaft 58 is fixed to a bearing 59 on the upper wall of the casing 10 and the lower end of the shaft is rotatably supported within the collar 60 carried by standard 61. As shown more clearly 35 in Fig. 2, the standard 61 is bolted to a side wall of the casing 10. Above the collar 60 is positioned a thrust bearing or washer 62 and above the washer 62 is a bearing 63 which is fixed to shaft 58. At the upper end of the shaft 58 and adjacent to the bevel gear 57 is a fixed collar 64 rigidly secured to shaft 58.

Secured to the collar 64 is a sliding link governor mechanism of a well known construction. The mechanism consists of link members 65 and 45 66 pivotally connected at their adjacent ends, and at their upper ends to the fixed collar 64 and at their lower ends to a sliding collar 67. Weights 68 may be secured to the links at their points of junction with each other. Between the upper collar 64 and lower collar 67 and inclosing the shaft 58 may be a compression spring 69. The collar 67 is preferably provided with an annular groove 70. A yoke 71 is fixed at its lower end to the valve stem 72 and the upper arms of the yoke are provided with inwardly extending pins 73 50 engaging the groove 70 of collar 67. The yoke 71 is held in alignment with the shaft 58 and valve stem 72 by means of pins 74 which extend, in pairs, from each side of the collar 60 to enclose the arms of the yoke as shown more clearly in Fig. 4. The yoke 71 is provided at its lower end where it joins the valve stem 72 with a collar 75 on which are mounted diagonally disposed 55 projections or lugs 76. The lugs 76 are adapted to strike the bifurcated end 35^a of the lever 35.

The valve F may be of any suitable construction. In the preferred construction illustrated, the valve body consists of a cylindrical casing 77 internally threaded at its upper and lower ends and with a threaded inlet 78 and a threaded outlet 79. Threadedly connected to the upper portion of the casing is a closure plate 80, apertured to receive the valve stem 72 and provided with a hollow boss 81 adapted to receive the packing 82 and a packing nut 83. Secured to the lower 60 end of valve stem 72 is a disk valve 84 against

which is clamped a bracing disk 85 by means of a nut 86 which threadedly engages the end of stem 72. In the lower end of the valve casing 77 is threadedly secured a plug 87 which is provided with a curved flow passage 88, the upper end of which is adapted to be closed by the valve disk 84. A small orifice or passage 89 provides communication between the upper chamber of the casing, which is recessed at 77^a, and the outer end 10 of flow passage 88.

In the operation of the apparatus, a coin or two, say quarters, are dropped through the open upper end of the coin slot 12. As shown more clearly in Fig. 1, the lower coin is engaged and supported by the forwardly extending shoulder 28 of plate 27. At the same time, the two coins depress the levers 14 and 15 into the position shown in which the contact fingers 21 are brought against the contact plates 22. The meeting of these contact points, or any pair of them, completes the circuit in which the motor is placed and immediately the motor starts in operation. It is desired to have at least two spring levers so that the apparatus may be kept in continuous operation after the lowermost coin has been released. 25 With the construction shown, when the lower coin is dropped, the second coin will hold the contact finger of lever 14 in contact until the release action is completed and then will drop to the position formerly occupied by the lower coin, 30 thus keeping the motor in continuous operation. The motor A drives through the series of reduction gears the arm 44 which in turn rotates the worm gear 43 and shaft 44. Thus, the disk 36 is slowly rotated, making, say, one revolution in twenty-four hours. When the pin 38 carried upon the adjustable plate 37 finally contacts with the finger 34 (after twenty-four hours), the finger is swung in the direction that the pin 38 is moving so as to elevate the pivoted ends of lever 32 and shank 30. This causes the plate 27 to drop so as to permit the shoulder 28 to clear the lower coin 35 40 26. The coin 26 drops into the receptacle 11. At the same time, the forwardly extending point 29 on plate 27 is swung forward so as to support the upper coin 26 against the swinging lever 14. The upper coin is held in this position until the pin 38 clears the finger 34. After the finger 34 is released from engagement with pin 38, it returns to its original position under the pull of spring 32^a which connects the pivotally connected 45 ends of shank 30 and shaft 32 to the upper wall of the cash receptacle 11. The plate 27 is thereby tilted rearwardly so that the point 29 clears the upper coin 26 and allows it to fall against the shoulder 28 which has moved back into its 50 initial supporting position.

As stated above, the supporting of the upper coin by the projection 29, during the interval when the pin 38 is clearing finger 34, keeps the 60 circuit closed and the motor in operation. Then when the plate 27 is swung back to its original position, the upper coin strikes the lower swinging lever 15 so that there is substantially no break in the flow of current to the motor. With this arrangement, the motor is constantly operating irrespective of the release of coins.

In apparatus for the present purpose, one of the chief difficulties is that the customer who deposits coins for the use of gas-time, may attempt to cheat the meter by disconnecting the 70 electrical connections by which current is supplied to the meter. Of course with the interruption of the current, the motor will not operate and the disk 36 will not rotate within the next 75^a

period of twenty-four hours to release the coin. The operation of the control apparatus, as will now be described, penalizes any attempt to cheat the meter by causing the coin to be released upon interruption of the current. The weighted governor is rotated by connection through gears 51, 56, 53, 52 and 50 by the pinion 48 carried by the motor shaft 49. With the motor constantly in operation, the governor will assume the position shown in Fig. 1 with the lower collar 67 in elevated position. However, when the motor stops and the link arms 65, 66, and weights 67 are no longer rotated, the collar 67 will drop to the lower position illustrated in Fig. 5. At the same time, the yoke 71 which is connected by pins 73 to the groove 70 of collar 67, will be depressed. As the yoke 71 drops, the projections or lateral lugs 76 strike the bifurcated end 35^a of the lever 35 and carry it to the depressed position illustrated in Fig. 4. By this movement, the inner end of the lever 32 and the adjacent end of shank 30 are raised, causing the plate 27 to tilt upon pivot 31. In this manner, the lower coin 36 is released by the same sort of movement that releases the coin after the lapse of twenty-four hours of use of the meter.

In the operation of the gas valve mechanism F, when the governor is in extended position as shown in Fig. 4, the valve disk 84 is in the lower position illustrated in Fig. 5 so as to close the outlet opening 88. Thus when the motor is not operated, either because the circuit is not closed by the placing of coins in the coin slot or because of tampering with the electrical connections, the valve 84 drops to closed position so as to prevent the use of fuel in the range. In this position, however, the orifice 89 permits the constant flow of gas to the pilot light. The quantity of gas thus supplied is not sufficient to supply the burners but does furnish sufficient fuel to maintain the pilot light. When the motor is in operation, the valve is drawn to the uppermost position illustrated in Fig. 5, the yoke 71 being raised by the pin connections with the groove 70 of collar 67.

It will be noted that with the valve control and valve mechanism illustrated, very slight effort is needed to reciprocate the closure valve 84. The contraction of the link arms of the governor readily raises the valve disk and, when the valve is closed by the dropping of the link arms, the closing operation is facilitated by the pressure of the gas upon the upper face of the disk 84. In raising the valve, the load of the parts is compensated by the upward pull of the arm 35 against the lugs 76, the spring 32^a being so tensioned as to practically balance the weight of the valve and associated parts.

The adjustable plate 37 permits the pin 38 to be shifted in position so as to permit an adjustment of the time period, within small limits, without changing the speed reduction gears, etc.

While space has been shown for depositing only about five coins, it will be readily understood that the apparatus may be modified so as to receive a much larger number of coins without departing from the principle of the invention. It will also be understood that many changes in details may be effected while employing the invention illustrated.

The foregoing detailed description has been given for clearness of understanding only, and no unnecessary limitations should be understood therefrom, but the appended claims should be

construed as broadly as permissible, in view of the prior art.

I claim:

1. In automatic control apparatus, driving mechanism, coin-controlled means for starting said mechanism, coin-release means, means driven by said driving mechanism for actuating said coin-release means to release a coin after a predetermined period, and control means actuated by said driving mechanism and adapted to release a coin on the stopping of said driving mechanism.

2. In apparatus of the character set forth, driving means, coin-controlled means for starting said driving means in operation, coin-release means, means driven by said driving means for actuating said coin-release means to release a coin after a predetermined period, control means adapted when operative to actuate said coin release means to release a coin, and connecting means between said control means and said driving means for rendering said control means inoperative as long as said driving means continues in operation.

3. In apparatus of the character set forth, driving means, coin-actuated means for starting said driving means, coin-release means, and valve-control means connected to said driving means and adapted to release a coin by actuating said coin-release means on the stopping of said driving means.

4. In apparatus of the character set forth, a motor, a coin slot, a contact member extending into said slot and adapted to be actuated by a coin to close the circuit in which said motor is placed, coin-release mechanism, means driven by said motor to actuate said coin-release mechanism after a predetermined period, and control means also driven by said motor and adapted to actuate said coin-release mechanism upon the stopping of said motor.

5. In apparatus of the character set forth, a motor, a coin slot, contact means in said coin slot adapted to be actuated by a coin to close the circuit in which said motor is positioned, coin-release means, means driven by said motor for actuating said coin-release means after a predetermined period to release a coin, and control means driven by said motor and adapted, when said motor is stopped, to release a coin in said coin slot.

6. In apparatus of the character set forth, a motor, coin-actuated means for closing the circuit in which said motor is placed, coin-release means, means driven by said motor for actuating said coin-release means to release a coin after a predetermined period, and valve-control means driven by said motor and adapted to actuate said coin-release means when said motor is stopped.

7. In apparatus of the character set forth, a motor, coin-controlled means for closing the circuit in which said motor is placed, coin-release means, means driven by said motor for actuating said coin-release means to release a coin after a predetermined period, a gas supply pipe, a valve therein, control means driven by said motor and adapted to open said valve when the motor is running and to close said valve when the motor stops, and means associated with said control means and actuated thereby for actuating said coin-release means when the motor stops.

8. In automatic control apparatus, a driving means, a coin slot adapted to receive a plurality of coins, coin-actuated means associated with said

slot for starting said driving means, coin-release means, means operated by said driving means for actuating said coin-release means for releasing the lowermost coin after a predetermined time, means for holding the coin thereabove against release during the releasing of the lowermost coin, said last-mentioned means then permitting the upper coin to drop to the position formerly occupied by the first-mentioned coin, and control means actuated by said driving means and adapted to actuate said coin-release means to release the lowermost coin on the stopping of said driving means.

9. In apparatus of the character set forth, a motor, a coin slot adapted to receive a plurality of coins, a plurality of contact members associated with said slot and adapted to be actuated by coins to close the circuit in which the motor is placed, coin-release means, means driven by the motor for actuating said coin-release means for releasing the lowermost coin after a predetermined period, means for holding the coin thereabove against release during the release of the lowermost coin, and then dropping said second-mentioned coin to the position formerly occupied by the first-mentioned coin, and means driven by said motor for automatically actuating said coin-release means to release the lowermost coin upon the stopping of said motor.

10. In combination, a motor, a coin slot, coin-actuated contacts within said coin slot adapted to be actuated by a plurality of coins to close the circuit in which said motor is placed, coin-release means, means driven by the motor for actuating said release means to free the lowermost coin after a predetermined period, means for maintaining the circuit closed during the releasing of the lowermost coin, and means driven by said motor and adapted to actuate said release means on the stopping of the motor.

11. In combination, a motor, a coin slot, coin-actuated contacts within said coin slot adapted to be actuated by a plurality of coins to close the circuit in which said motor is placed, coin-release means, means driven by the motor for actu-

ating said release means to free the lowermost coin after a predetermined period, means for maintaining the circuit closed during the releasing of the lowermost coin, and slidable governor means driven by said motor and adapted to actuate said release means on the stopping of the motor.

12. In apparatus of the character set forth, driving means, coin-controlled means for starting said driving means, coin-release means, means driven by the motor for actuating said release means after a predetermined period, and a governor equipped with a slidable collar, said governor being driven by the motor and when driven, adapted to support the collar in raised position, and when idle, to depress said collar to a lower position, and means operated by said collar for actuating the coin-release mechanism when the collar is in lower position.

13. In apparatus of the character set forth, driving means, coin-controlled means for starting said driving means, coin-release means, means driven by said driving means for actuating said release means after a predetermined period, a gas supply pipe, a valve therein, valve-control means driven by said motor and adapted to open said valve, said control means, upon the stopping of the motor, serving to close said valve, and means associated with said control means for actuating said coin-release means upon the stopping of the motor.

14. In automatic control apparatus, driving means, coin-control means for starting said driving means, coin-release means, means actuated by said driving means for actuating said coin-release means after a predetermined period, a fluid supply pipe, a valve therein, control means actuated by said driving means and adapted to open said valve when said driving means is operating, and means associated with said control means and actuated thereby for actuating said coin-release means when said driving means stops.

FRED E. WOOD.
